Inventor:
Alexander R. Stevenson, Jr.,

by *Myron S. Joint*
His Attorney.

UNITED STATES PATENT OFFICE.

ALEXANDER R. STEVENSON, JR., OF SCHENECTADY, NEW YORK, ASSIGNOR TO GENERAL ELECTRIC COMPANY, A CORPORATION OF NEW YORK.

BALANCING MEANS FOR OSCILLATING CYLINDER MACHINES.

Application filed March 26, 1926. Serial No. 97,794.

My invention relates to machines which comprise a cylinder, a piston therein and a shaft, and particularly to such machines in which the cylinder oscillates and the piston engages an eccentric member rotatable with the shaft. It is well known that when such a machine is operated at relatively high speed the rapidly moving parts may produce considerable vibration. A certain amount of this vibration has been avoided in the past by applying a counterweight to the shaft to partially balance the piston and its connection with the shaft. A partial balance only was produced for the reason that it was known that if the counterweight were made sufficiently heavy to effect a complete balance of the parts in the general direction of the cylinder to reduce vibration in that direction it would very much overbalance the parts in the transverse direction and would produce excessive vibration in the latter direction. Hence it has been customary to make a compromise in the balance in these two directions by making the counterweight approximately only half of what it should be to balance the parts in the direction of the cylinder although greater than it should be to balance the parts in the transverse direction.

It is an object of my invention to provide an improved machine of this character in which the moving parts are substantially balanced both in the general direction of the cylinder and in the direction transverse thereto, whereby the machine may be operated at a relatively high speed without producing an objectionable amount of vibration.

My invention will be better understood from the following description taken in connection with the accompanying drawing, and its scope will be pointed out in the appended claims.

Referring to the drawing, Fig. 1 is a perspective view of one embodiment of my invention; Fig. 2 is a top plan view of the same; and Fig. 3 is a longitudinal section thereof.

While my invention is equally applicable to either an engine or a pump, I have chosen to illustrate it as applied to the compressor of a refrigerating machine such as that disclosed in the copending application of

Clark Orr 756,336, filed Dec. 16, 1924, and assigned to the same assignee as the present application.

In the drawing the drive shaft 1 has an eccentric 2 thereon which is engaged by the eccentric strap portions 3 and 4 respectively of the two pistons 5 and 6. The frame 7 which provides a bearing for the shaft 1 has two flat bearing faces 8 and 9 on which the two oscillating cylinders 10 and 11 respectively rest. Each cylinder has a trunnion 12 on its lower side journaled in the frame 7. Each cylinder is shown held down on its seat by means of a spring 13 which at its upper end bears against a part of the frame and at its lower end carries a plate 14 which bears against a ball 15 resting in a depression in the top of the cylinder. Each cylinder is also shown provided with an intake port 16 which cooperates with a suitable port in the frame 7 and with an exhaust valve 17 which is covered by a muffler 18.

The counterweight, which I have shown as comprising the two weights 20 and 21, is applied to the shaft on the side opposite to the center of the eccentric 21. I construct this counterweight such that it substantially balances the eccentric and the two pistons in the general direction of the cylinders, that is, when the shaft is at right angles to that shown in Fig. 2, the moving parts are substantially in static balance in the direction of the cylinders. Weight 20 is shown secured to the upper face of the eccentric 2 by means of the plates 22 and the weight 21 is shown secured to the shaft by means of the arm 23 below the frame 7. The entire mass of the counterweight may if desired be located in a single weight but better results are obtained if the mass is divided, one part being arranged above and the other below the eccentric, the relative weights of the parts being of course proportioned in accordance with their spacing from the center of the eccentric.

It is well known that if the counterweight is thus made sufficiently heavy to balance the parts in the direction of the cylinders it will be far too heavy to balance the parts in the transverse direction since when the parts are in the position shown in Fig. 2 the pistons are partially supported by the cylinders. The cylinders

moreover have their centers of gravity approximately coincident with their pivotal centers.

In accordance with my invention, after thus balancing the parts in the direction of the cylinders I produce a condition of balance also in the transverse direction by adding weight to the cylinders between their pivoted centers and the shaft. For this purpose I have shown each cylinder provided with a pair of diverging arms or counterweights 25 and 26 which have the effect of shifting the center of gravity of each cylinder, otherwise approximately coincident with its pivotal center, to a new position between its pivotal center and its open end. The arms 25 and 26, it will be noted, move in the opposite direction to that of the counterweight when the parts pass the position shown in Fig. 2 and a proportionate amount of their weight is added to that of the eccentric which must be balanced by the counterweight. By suitably proportioning these arms a condition of substantial static balance is obtained relative to the transverse direction or direction at right angles to the cylinders. Inasmuch as the cylinders have only oscillating movement the presence of the arms 25 and 26 does not appreciably affect the balance of the parts in the direction of the length of the cylinders. It will therefore be seen that in my machine the moving parts are substantially balanced both in the direction of the cylinders and in the transverse direction and for this reason the machine may be operated at a relatively high speed without an objectionable amount of vibration resulting therefrom.

What I claim as new and desire to secure by Letters Patent of the United States, is:—

1. In combination, a rotatable shaft, an oscillatable cylinder, a piston therein, a drive connection between the shaft and the piston, means associated with the shaft for producing substantial balance in the longitudinal direction of the cylinder and means associated with the cylinder and cooperating with said means for producing substantial balance

in a direction transverse to the longitudinal direction of the cylinder.

2. A compressor comprising a drive shaft having an eccentric thereon, a pivotally mounted cylinder arranged at one side thereof, a piston in the cylinder engaging said eccentric, and a counterweight carried by the shaft for balancing the eccentric and the piston in the direction of the cylinder, said cylinder being constructed to have its center of mass located between its pivotal center and the shaft and said mass being such that substantial balance is obtained in a direction at right angles to the cylinder.

3. A compressor comprising a drive shaft, an oscillatable cylinder, a piston therein having an eccentric connection with the shaft, counterweight means rotatable with the shaft for producing substantial balance in the longitudinal direction of the cylinder, and counterweight means carried by the cylinder and cooperating with said first means for producing substantial balance in the direction at right angles to the longitudinal direction of the cylinder.

4. A compressor comprising a drive shaft having an eccentric thereon, a pair of pivotally mounted cylinders arranged on opposite sides thereof, a piston in each cylinder having an eccentric strap engaging said eccentric, a counterweight carried by the shaft for balancing the eccentric and the pistons in the direction of the cylinders, and counterweights carried by the cylinders between their pivotal centers and the shaft.

5. A compressor comprising a drive shaft having an eccentric thereon, a pair of pivotally mounted cylinders arranged on opposite sides thereof, a piston in each cylinder having an eccentric strap engaging the eccentric, and a counterweight on the shaft arranged on the side thereof opposite to the eccentric, said cylinders each having a pair of extensions forming weights projecting toward the shaft and arranged in opposite sides of the piston.

In witness whereof, I have hereto set my hand this 25th day of March, 1926.

ALEXANDER R. STEVENSON, Jr.
